UNITED STATES PATENT OFFICE.

WALTER RICHARD HOLTTUM, HARRY GEORGE, AND RALPH LESTER, OF LUTON,
ENGLAND.

HAT-BLOCKING MACHINE.

Application filed August 8, 1922. Serial No. 580,449.

To all whom it may concern:

Be it known that we, WALTER RICHARD HOLTTUM, subject of the King of Great Britain, and HARRY GEORGE and RALPH LESTER, of Brown and Green Limited, British firm, residing at 14 Dallow Road, Luton, Bedfordshire, England, and Windsor Street, Luton, Bedfordshire, England, respectively, have invented new and useful 10 Improvements in Hat-Blocking Machines; and we do hereby declare the following to be a full, clear, and exact description of the invention, such as will enable others skilled in the art to which it appertains to 15 make and use the same.

This invention relates to machines for blocking straw, felt or velour hats and particularly to machines wherein blocking is effected by means of a steam or otherwise 20 internally heated female mould or pan and a male mould in the form of an expansible rubber or other bag carried by a cap member said bag operating to press the material against the interior surface of the heated 25 pan to form the crown the brim being simultaneously formed by compression between the opposing surfaces of the cap and the pan.

An object of the present invention is to 30 provide a hat blocking machine in which the female portion or portions of the mould is or are capable of being moved out of alignment with the male portion of the mould whereby the positioning of the blanks 35 or the removal of the shapes from the female portion or portions of the mould is effected in safety and in a more convenient manner than heretofore.

A further object of the invention 40 is to provide a hat blocking machine in which the operation of blocking may be substantially continuous.

The invention consists broadly of a hat 45 blocking machine which comprises a two part mould consisting of a male portion and a female portion which latter portion is adapted to be moved axially relative to the male portion wherein the female portion is adapted to be moved laterally out of alignment with the male portion when the two 50 portions are in the separated position.

A hat blocking machine according to one embodiment of the invention comprises a stationary cap carrying one part of the

mould and one, two or more pans carrying 55 the other part of the mould which pans are pivoted whereby the same may be swung in a horizontal plane alternatively into and out of position beneath the stationary cap and means for raising each positioned pan 60 vertically towards the cap to effect the blocking operation and for lowering the same at the completion of such operation.

The pans are heated by means of concealed steam which is passed into the interior of surrounding chambers or in the known manner through suitably arranged pipes or passages. Means are also provided whereby a cooling fluid such as air or cold 70 water may be passed into the cap and the interior of the bag and also when desired into the aforesaid steam spaces for cooling purposes. This permits of the blocking of hats to any desired finish such as a completely rigid hat or a hat having a rigid 75 brim and soft crown or a completely soft hat.

In order that the invention may be clearly understood an embodiment of the same will now be described by aid of the accompanying drawings in which:

Fig. 1 is a front elevation of the machine shewing the pans swung outwards and the ram lowered.

Fig. 2 is a plan of the same.

Fig. 3 is a front elevation shewing one of the pans in position for blocking and the ram raised.

Fig. 4 is a section of one of the pans with the mould removed and drawn to an 90 enlarged scale.

Figs. 5 and 6 are a sectional plan and vertical section respectively of driving gear and gear box.

Figs. 7 and 8 are end elevation and plan 95 respectively of one form of belt striking gear.

The hat blocking machine illustrated in the drawings comprises a hollow cap member 1 of substantially conventional form 100 the lower open end of which is normally closed by a rubber or the like bag 2 constituting the male portion of the mould. This cap is provided with an air bottle 3 and a pressure gauge 4 and the same is 105 adapted to receive air or water under pressure through an inlet pipe 5. This cap is supported upon a pair of turned vertical

columns 6 which rise up from a bed plate 7. This bed plate is provided with or disposed within a suitable pan 8 which serves to catch and collect all moisture. The base 9 of each column is of enlarged diameter as shewn and the top face of each is formed with a faced flange 10 each of which flanges is formed with a cut away portion 11 for a purpose hereafter to be explained.

10 Slidably and pivotally mounted upon each of these columns is a bracket 12 to each of which is bolted a pan 13. These pans are hollow and are adapted to receive the female portion 14 of the mould the upper edges of which rest upon the annular faces 15 of the pans. Beneath each of these faces is a circular cored passage 16 to which concealed steam is admitted during the blocking operations for the purpose of heating up 20 the edges of the mould and producing stiff brims on the blocked hat shapes. Steam is also adapted to be admitted to the interior of each pan in the space around the mould by way of the three openings 17 for the purpose of initially heating the 25 moulds at the commencement of blocking operations. During normal working this steam is shut off and admitted only to the cored passages 16. Handles 18 are provided 30 on each pan for use in swinging the same about the columns 6.

The base of each bracket 12 is provided with a depending lug 19 which rest in the cut away portions 11 and constitute, with 35 the ends of such cut away portions, stops for limiting the inward and outward positions of the pans. The bottom of each pan is formed with a flat boss 20 which, when a pan is in the inward position, rests upon 40 the upper surface of the head 21 of a ram 22. This ram, see Fig. 6, is threaded internally and such threaded portion is engaged by a screwed spindle 23 which is adapted to be rotated for the purpose of raising or 45 lowering the ram through the medium of a worm 24 and a worm wheel 25 keyed upon or otherwise secured to the lower end of the screwed spindle 23. The worm 24 is driven in either direction by means of a 50 pair of driving pulleys 26 and 27 through the medium of gearing. This gearing is contained within a casing 28 and comprises a pair of toothed wheels 29 mounted upon a shaft 30 which is driven by the pulley 26 and a further toothed wheel 31 mounted 55 upon a hollow sleeve 32. This sleeve is mounted co-axially upon the shaft 30 and the same is adapted to be driven by the other pulley 27. The toothed wheels 29 mesh with further toothed wheels 33 mounted upon the worm spindle 34 and upon 60 opposite sides of the worm. The toothed wheel 31 serves to drive the worm shaft in the reverse direction by means of a toothed wheel 35 mounted thereon and an inter-

posed pinion 36. A loose pulley 37 is provided disposed between the driving pulleys 26 and 27.

It is preferred that the raising and lowering of the ram shall be automatic in action 70 with the exception of the initial starting operations which are preferably manually effected. For this purpose we illustrate one means of controlling the position of the belt striking fork 38. These means comprise a 75 cam 39 which is carried by and moves with the striking rod 40 and is normally maintained in the neutral position shewn in Fig. 8 by means of a pair of springs 41 and 42 arranged co-axially around the rod 40 on 80 opposite sides of the cam and between the cam and a pair of bearing brackets 43. Co-acting with the edge of this cam is a roller 44 carried upon the lower end of a cranked bracket 45 the other end of which is attached to and moves with the head 21 of the ram 22. In operation the striking rod 45 is manually pulled longitudinally so as to shift the position of the cam to one side or the other of the neutral position and to 90 simultaneously compress one of the springs. This movement also operates to move the striking fork so as to bring the belt into engagement with either one of the pulleys 26 or 27. Assuming that the belt is 95 engaged with the pulley 26, this operates to raise the ram 22 and with it the roller 44 which is free to travel up one side of the cam during which traversing movement the cam is thereby held against the tension of 100 the spring 41. The ram therefore continues to rise until the roller has reached the top of the cam when the tension on the spring being relaxed the same operates to return the cam striking fork and belt to its neutral 105 position. The ram remains in the elevated position until the striking rod is again operated as before but in the opposite direction with the result that the roller commences to travel down the opposite side of the cam 110 until at the bottom the spring 42 returns the cam again to its neutral position. It will thus be seen that the blocking operations are substantially continuous inasmuch as when one pair is in the blocking or inward position the other is swung out clear of the machine for the removal of the completed hat shape and the positioning of a further blank after which it is again swung into position above the ram when the other 120 pan has been similarly removed.

It will of course be appreciated that any form of gearing may be employed in connection with the plunger raising and lowering mechanism the gearing described and 125 illustrated being given merely by way of example and either hand or power operation may be used.

What we claim is:—

A hat blocking machine comprising a 130

base, a pair of spaced vertical standards rising therefrom, a mold composed of a male member and a pair of female members, the male member being permanently mounted between said standards and the female members being mounted one on each standard for rotation with respect thereto and for vertical sliding movement therealong, whereby they may alternately be swung into alignment with the male member and be operatively and inoperatively disposed with respect thereto.

In witness whereof we have signed this specification in the presence of two witnesses.
